INVENTOR

UNITED STATES PATENT OFFICE

96,080

DESIGN FOR A HAT

Sol Apfel, New York, N. Y.

Application May 17, 1935, Serial No. 56,882

Term of patent 3½ years

To all whom it may concern:

Be it known that I, Sol Apfel, a citizen of the United States of America, residing in Manhattan, county of New York, and State of New York, have invented a new, original, and ornamental Design for a Hat, of which the following is a specification, reference being had to the accompanying drawing, forming part thereof, wherein,

The heavy lines and shading on the crown of the hat, represent folds.

I claim:

The ornamental design for a hat, substantially as shown and described.

SOL APFEL.
